STOCKING AND SOCK HOLDER

Filed March 8, 1928

Fig. 3.

Inventor:

Otto Adam

UNITED STATES PATENT OFFICE

OTTO ADAM, OF BERLIN, GERMANY

STOCKING AND SOCK HOLDER

Application filed March 8, 1923, Serial No. 260,191, and in Germany March 19, 1927.

This invention relates to stocking and sock holders of that kind in which a portion of the upper rim of the stocking or sock is clamped fast between two members suspended from a (generally elastic and adjustable) band attached at its upper end either to a part of the underwear especially in the case of ladies' stockings, or to another (generally elastic and adjustable) band encompassing the respective leg, especially in the case of gentlemen's socks. Stockings and sock holders of this type suffer from certain drawbacks dealt with hereinafter, and it is the object of the present invention to overcome

10 the respective drawbacks.

The invention is illustrated diagrammatically and by way of example on the accompanying drawing on which Figure 1 is a front-view of a stocking or sock holder designed according to this invention and intended for gentlemen's sock, Figure 2 a front-view of a holder for ladies' stockings, the upper portion of the suspending band being left away, and Figure 3 a vertical section through the front members of Fig. 1.

The clamping members proper are the members *f* and *g*, each of which is provided with an upper slot *i* and *k* through which the ends of a short band *e* connecting said members with one another are passed. The band *e* extends also through a slot *l* provided in the so-called shield *a*. The lower end of the member *g* is provided with a slot *m*, and the lower end of the member *f* is so shaped as to form a hook *h* adapted to engage the slot *m* in the manner shown in Fig. 3. When the hook *h* is disengaged from the slot *m*, that is to say, when the member *f* is disengaged from the member *g*, and a stocking or sock is to be attached to the holder, a portion at the front of the rim of that stocking or sock is shoved over the hook *h* and this latter with that portion of the stocking or sock upon it is then shoved through the slot *m*, whereby the three parts are securely connected with each other and the respective stocking or sock is securely suspended from the shield *a* by the intermediary of the band *e*.

If the holder is intended for gentlemen's

socks the shield *a* is shaped as in Fig. 1, and if it is intended for ladies' stockings it is shaped as in Fig. 2. In the first case the shield *a* is provided with a slot *p* located on one side of the shield and with a semi-circular cut-out *r* located upon the other side of the shield *a*, and a rounded-off tongue *c* projects forth into this cut-out and extends in the direction to the slot *p*. The adjustable rubber band *b* with its clasp *q* is attached to the shield by means of the slot *p*, and a loop *d* adapted to receive the tongue *c* in it, as shown in Fig. 1, is secured to the other end *t* of the band *b*.

If the shield is intended for ladies' stockings, its shape is that shown in Fig. 2, which the shield *a'* is provided with an upper slot *n* through which passes the suspension band *o*, of which only the lower part is shown in the figure.

Owing to the provision of the tongue *c* and the loop *d* in the constructional form shown in Fig. 1, that is to say, owing to the omission of a hook and an eye, as otherwise used, the connecting members are prevented from pressing upon the leg and rubbing on it. Furthermore, owing to the particular configuration of the clamping members *f* and *g* the stocking or the sock can be clamped fast very easily and without being in the least damaged, in that a comparatively long portion of it is clamped fast between said members without any stretching of the respective meshes, even if the mesh threads are thin. The hold of the sock or stocking between the clamping members is the more strongly the more the sock or stocking effects a downwardly directed pull upon said members, and a spontaneous disconnection of the parts concerned cannot possibly take place. And, as finally, the shield and all parts below it are flat none of them can exert a disagreeable pressure upon the body portion located below it, nor can any part get entangled with a neighbouring part of the underwear or the like.

Apart from the bands *e* and *b*, the other members of the holder do not consist of metal but of a material which cannot be affected by moisture, as for instance celluloid, from

which the solid members can be manufactured in a very easy manner.

I claim:

1. A stocking and sock holder, comprising, in combination, an elastic garter; a loop at one end thereof; a rigid shield connected with the other end of the garter; a flat tongue in said shield and adapted to be coupled with said loop; two separate rigid members, of which one has a slot at one end and the other forms at one end a hook adapted to be put through said slot to hold fast the rim of a sock or stocking; and a pliable member connecting said two members with one another and passing through a slot in the said shield.
2. A sock and stocking holder, comprising, in combination, two practically vertical rigid members, of which one has a slot near its lower end and the other forms at its lower end a hook adapted to be put through said slot of the first mentioned member to take hold of the rim of a sock or stocking; a band connected at its two ends with the other ends of said two members; a vertical shield having in its lower portion a horizontal slot through which said band is passed so as to suspend said two members from said shield this latter having another slot in one of its sides, and having a cut out portion in the other side, and a tongue projecting forth into said cut-out portion; an elastic garter having one of its ends attached through said other slot of the said shield, and a loop attached to the other end of said garter and adapted to be coupled with said tongue substantially as set forth.

In testimony whereof I affix my signature.
OTTO ADAM.
